UNITED STATES PATENT OFFICE.

THOMAS McCABE, OF YORKVILLE, OHIO.

PLATE-LIFTING MECHANISM FOR ROLLING MILLS.

Application filed June 3, 1922. Serial No. 565,730.

To all whom it may concern:

Be it known that I, THOMAS McCABE, a citizen of the United States, residing at Yorkville, Ohio, have invented a certain new 5 and useful Improvement in Plate-Lifting Mechanisms for Rolling Mills, of which the following is a full, clear, and exact description, such as will enable others skilled in the art to which it appertains to make and use 10 the same.

This invention relates to a plate lifting mechanism for rolling mills of the same general type as the plate lifting mechanism described in my U. S. Patent No. 1,418,815, 15 dated June 6, 1922, namely, a plate lifting mechanism that comprises a receiving table arranged at the rear of the rolls of the mill for receiving a rolled plate as it is discharged from said rolls, and vertically movable plate 20 lifters arranged at the opposite sides of said table and adapted to engage the plate on the table and move it upwardly into such a position that it can be grasped and pulled forwardly over the top roll of the mill by the 25 operator standing at the front of the mill.

The main object of my present invention is to provide a plate lifting mechanism of the general type referred to which is so 30 constructed that it can be easily moved into such a position that it does not interfere with workmen engaged in repairing or removing the rolls of the mill.

Another object is to provide a plate lifting mechanism of the type that comprises plate lifters which move upwardly and downwardly, that is constructed in such a way that the jar or back lash on the gears of the operating mechanism for the plate 40 lifters will be absorbed when the plate lifters come to rest either in their elevated position or in their depressed position.

Another object is to provide an operating mechanism of novel construction for tilting the receiving table so as to discharge a plate therefrom, and other objects of my invention are to reduce the size and simplify the construction of a plate lifting mechanism of the general type disclosed in my pending application previously referred to.

To this end I have devised a plate lifting mechanism for rolling mills, which, briefly described, consists of a receiving table adapted to be arranged at the rear of the rolls of a plate rolling mill, a plate lifting means for lifting a plate from said table and

moving it upwardly into such a position that it can be pulled forwardly over the top roll of the mill by the operator in charge of the mill, and means for enabling said table and plate lifting means to be moved bodily into such a position that ample space is provided at the rear of the rolls of the mill for workmen who are repairing said rolls or removing them from the supporting frame of the mill. In the preferred form of my invention, as herein illustrated, the receiving table and the plate lifting means are carried by a movable supporting frame which is constructed in such a manner that it can be tilted rearwardly so as to carry the receiving table and the plate lifting means out of the zone at the rear of the rolls of the mill in which the workmen stand during the operation of removing the rolls, 75 but I wish it to be understood that my invention is not limited to a mechanism of the particular construction herein illustrated, as my broad idea contemplates the use of any shiftable supporting structure 80 for the receiving table and the plate lifting means that can be moved quickly and easily into one position so as to arrange said elements in an inoperative position out of the way of workmen standing behind the rolls 85 of the mill, and thereafter restored easily to its normal position, so as to arrange said elements in operative relationship with the rolls of the mill.

Figure 1 is a top plan view of a plate lifting mechanism embodying my present invention arranged in operative relationship with a rolling mill. 90

Figure 2 is a vertical longitudinal sectional view, taken on the line 2-2 of Figure 1, looking in the direction indicated by the arrows. 95

Figure 3 is a vertical longitudinal sectional view, taken on the line 3-3 of Figure 1, looking in the direction indicated by the arrows with a portion of the rolling mill broken away. 100

Figure 4 is a front elevational view of the plate lifting mechanism, the rolling mill not being shown. 105

Figure 5 is a rear elevational view of the plate lifting mechanism, partly in vertical transverse section.

Figure 6 is a top plan view of the clutch member on the crank shaft and a portion of 110 the constantly rotating pulley that actuates the same.

Figure 7 is a transverse sectional view of said clutch member.

Figure 8 is a side elevational view of said clutch member.

5 Figure 9 is a top plan view of said clutch member.

Figure 10 is a vertical longitudinal sectional view of the plate lifting mechanism, taken on the line 10—10 of Figure 1, looking in the direction indicated by the arrows.

Figure 11 is a vertical longitudinal sectional view, taken on the line 11—11 of Figure 1, looking in the direction indicated by the arrows; and

15 Figure 12 is a vertical longitudinal sectional view, taken on the line 12—12 of Figure 1, looking in the direction indicated by the arrows.

Referring to the drawings which illustrate the preferred form of my invention, 20 A and A' designate the top and bottom rolls of a conventional plate rolling mill, B designates a receiving table that is normally arranged at the rear side of said rolls with its front end positioned in close proximity to same so as to receive a plate that is discharged from the rolls, and C and C' designate vertically movable plate lifters arranged at opposite sides of the table B 25 and adapted to be moved upwardly into the position shown in broken lines in Figure 3, so as to lift a plate from the receiving table and move said plate upwardly into such a position that the operator standing 30 in front of the mill can grasp the front end of said plate and pull it forwardly over the top roll of the mill.

The receiving table, the plate lifters and the mechanism that is used for actuating 40 said elements are carried by a supporting frame which is mounted in such a manner that it can be tilted rearwardly into the position shown in broken lines in Figure 2, in the event it becomes necessary to repair or 45 remove the rolls A and A' of the mill. The supporting frame of the machine herein illustrated is composed of four vertically-disposed frame members 1 tied together by suitable transversely-disposed tie members 50 and pivotally mounted on two pedestals or uprights 2 arranged at the rear end of a stationary base plate 3, as shown in Figure 5, said frame members 1 being arranged in pairs at opposite sides of the machine, as 55 shown in Figure 1, so that the receiving table and the plate lifters at the opposite sides of same will be positioned between the two center frame members.

60 *Plate lifters.*

Both of the plate lifters are of the same construction, and therefore, I will refer only to the plate lifter C in describing the construction and operation of the plate lifter 65 means of the machine. The plate lifter

C is of substantially the same length as the receiving table B and comprises a horizontally-disposed plate receiving portion that projects laterally from one side of a vertically-disposed portion 4 that extends upwardly above the horizontally-disposed plate receiving portion, as shown in Figure 5, so as to serve as a side guide for the plate that is discharged from the rolls of the mill onto the receiving table B, the plate lifters C and C' being tied together at their rear ends by a transversely-disposed rod 5 connected to upwardly-projecting arms 6 on said plate lifters. The front end of the plate lifter C is supported by a swinging link 7 provided at its upper end with a counterweight 8 and having its lower end pivotally connected to the vertically-disposed portion 4 of the plate lifter, preferably by means of a rigid pin 9 in said portion 4 that turns in a bearing in the lower end of said link 7. The rear end of said plate lifter is supported by a swinging link 10 provided at its upper end with a counterweight 11 and having its lower end pivotally connected by a horizontally-disposed shaft 12 to a movable bearing 13 that is slidingly mounted in an oblong-shaped guideway 13^a formed in the vertically-disposed portion 4 of the plate lifter, said shaft 12 being supported by a block 14 carried by the link 10 and connected to same in such a way that it can be raised and lowered so as to increase or decrease the effective length of the link, and thus enable the rear end of the plate lifter to be moved higher than the front end of the plate lifter, so as to arrange the plate lifter in such a position that it is inclined downwardly towards the rolls of the mill. In other words, if it is desired to 105 have the plate lifters inclined downwardly, more or less, when said plate lifters are arranged in elevated position, the blocks 14 on the links 10 are moved outwardly more or less towards the outer ends of said links 10. In the form of my invention herein illustrated the block 14 is adjustably connected to the link 10 by fastening devices 15, as shown in Figure 5, that can be moved 110 vertically in elongated slots 16 formed in a machined surface on the link 10 on which the block 14 slides and an adjusting screw 17 is arranged in the lower end of the link so as to facilitate accurate adjustment of 115 said block. The front link 7 swings between two of the frame members 1 at one side of the machine and is rigidly connected to a short, horizontally-disposed shaft 18 that is journaled in bearings 19 connected to the upper edges of said frame members, the rear link 10 also being arranged between said frame members and being rigidly connected to a horizontally-disposed shaft 20 that is journaled in bearings 21 on 120 said frame members. The shafts 18 and 20 125

are provided with rigid pinions or gears 22 and 23, respectively, that mesh with a segmental-shaped rack 24 on the upper edge of an oscillating actuating member 25 that is rigidly connected to a horizontally-disposed shaft 26 arranged transversely of the machine and journaled in bearings in the frame members 1, and means is provided for rocking said shaft 26 first in one direction 5 so as to cause the rack 24 to co-operate with the pinions 22 and 23 to swing the links 7 and 10 in a direction to move the plate lifter C upwardly into the position shown in broken lines in Figure 3, and for thereafter 10 rocking said shaft 26 in the reverse direction so as to restore said plate lifter to its normal position in horizontal alignment with the receiving table B, the pinions that are associated with the links which sustain 15 the other plate lifter C' being operated by a separate actuating member 25 rigidly connected to the shaft 26 so as to cause both plate lifters to move in unison.

In the machine herein illustrated the 20 means for rocking the actuating members 25 consists of a crank shaft 27 arranged at the rear end of the base plate 3, as shown in Figure 5 and provided with a crank arm 28 that is connected by means of a link 29 to an arm 30 on the rock shaft 26 to which the actuating members 25 are connected, as shown in Figure 10, said crank shaft 27 being driven by a pulley 31 which is adapted to be connected to said crank 25 shaft by a clutch under control of the operator standing in front of the rolling mill. The pulley 31 is driven by a belt 32 that passes over a pulley 33 on a transversely-disposed drive shaft 34, as shown in Figure 30, that can be driven in any preferred manner, and the clutch that I prefer to use for connecting the pulley 31 with the crank shaft 27 consists of a clutch member 35 rigidly connected to the crank shaft 27 and 35 provided with a spring-actuated plunger 36 arranged in one side of same in such a manner that it will project laterally and engage one of a plurality of clutch jaws 37 formed on the hub 31^a of the pulley 31 when said plunger 36 is in its operative position, namely, projected outwardly beyond the side face of the clutch member 35, as shown in Figure 6. The plunger 36 is normally held 40 retracted by one or the other of a pair of pivotally mounted bell-crank-shaped tripping dogs 38 and 38^a carried by one of the frame members 1, as shown in Figure 3, and arranged so that the short arms of same lie in a vertical plane between the side face of 45 the clutch member 35 and the ends of the clutch jaws 37^a on the hub of the pulley 31. The plunger 36 has a head 36^a whose upper edge is beveled at 36^b, as shown in Figure 9, so that when it strikes against the short arm 50 of one of the tripping dogs 38 or 38^a, it will be moved inwardly into its retracted position out of engagement with the clutch jaw 37 on the hub of the pulley 31. The tripping dogs 38 and 38^a are so arranged that they will operate on the plunger 36 of the clutch 55 member 35 at two different points and are connected together at their upper ends by a link 39 whose front end is joined to a rod 40 that leads forwardly to a bell crank lever 41 which is, in turn, connected by means of a link 42 to a foot treadle 43. Normally, the tripping dogs 38 and 38^a are held in the position shown in Figure 3 by a spring 44 connected at one end to one of the frame 60 members 1 and at its opposite end to the tripping dog 38^a, thereby holding said dogs in such a position that the hook-shaped ends of same project into the space between the side of the clutch 35 and the ends of the jaws 37 on the hub of the pulley 31. When 65 the foot treadle 43 is depressed so as to move the hook-shaped ends of the tripping dogs 38 and 38^a outwardly or out of the space between the clutch member 35 and the ends of the jaws on the hub of the pulley 70 31, the spring 36^c that is combined with the plunger 36 immediately pushes said plunger outwardly into such a position that it will engage one of the clutch jaws 37 on the pulley 31, thereby causing the crank shaft 75 27 to make a half revolution and come to rest when the plunger 36 in the clutch member 35 strikes against the hook-shaped end of the other tripping dog, the engagement of said dog with the inclined surface 36^b on 80 the head of the plunger causing the plunger to be retracted or disengaged from the clutch jaw on the pulley 31. In operating the clutch the operator merely presses down on the foot treadle 43 and then immediately 85 releases said treadle so that the spring 44 will restore the tripping dogs to their operative position, in the path of the head of the plunger 36 on the clutch member 35.

In order to absorb the shock produced by the sudden stopping of the crank shaft 27, or, in other words, to break the sudden jar or back lash on the segmental racks of the actuating members 25 and the pinions with which said racks co-operate, when the 90 plate lifters come to rest in their elevated position and come to rest in their depressed position, the shafts 18 and 20 at the opposite sides of the machine to which the pinions 22 and 23, respectively, are connected are provided with arms 45, as shown in Figure 3, that are connected together by coiled springs 46.

The purpose of equipping the links 7 and 10 with counterweights is to assist the actuating members 25 to raise and lower the plate lifters, and while these counterweights can be constructed in various ways, I prefer to construct each counterweight from a casting formed as an integral part of the link 100

with which it co-operates and made hollow or provided with pockets 47, as shown in Figure 10, that are adapted to be filled with lead or other relatively heavy material, thereby producing an inexpensive counter-weight that is small enough to travel between the frame members 1 of the machine.

Receiving table.

- 10 The receiving table B preferably comprises a horizontally-disposed top portion provided with a depending web 48 that is equipped at its rear end with a horizontally-disposed sleeve 49 which turns on a transversely-disposed shaft 50 carried by the frame members 1, the front end of said table normally resting on a transversely-disposed tie rod 50^a that is connected to the center members 1 of the tilting frame 20 of the machine. A rigid arm 51 that projects forwardly from one end of the sleeve 49, as shown in broken lines in Figure 11 and in full lines in Figure 5, is connected by means of a link 52 to an arm 53 on a horizontally-disposed shaft 54 which is journaled in the frame members 1, and means is provided for rocking said shaft 54 so as to tilt the front end of the receiving table upwardly when it is desired to discharge a plate from the rear end of said table. In the form of my invention herein illustrated the means for rocking the shaft 54 consists of an arm 55 on said shaft, shown in Figure 12, a link 56 leading forwardly from said arm and pivotally connected by a bolt 57 to a link 58 which leads forwardly to a hand-operated lever 59 arranged in such a position that it can be grasped by the operator standing at the front of the mill, the link 56 being supported by a swinging link 60, which, in turn, is loosely mounted on a transversely-disposed tie rod 61 connected to the frame members of the machine. When it becomes necessary to tilt the movable supporting frame of the machine, as hereinafter described, the bolt 57 is removed so as to disconnect the links 56 and 58 and permit the link 56 to move with the supporting frame.
- 50 *Mechanism for tilting the movable supporting frame.*

As previously stated, the movable supporting frame composed of the frame members 1 is pivotally mounted on the pedestals or uprights 2 at the rear end of the stationary base plate 3 of the machine. While the particular means that is used for pivotally mounting the supporting frame on said pedestals is immaterial, so far as my invention is concerned, I prefer to provide the pair of frame members 1 at the left hand side of the machine with a sleeve 62, shown at the right of Figure 5, that turns freely in one of the uprights 2, said sleeve being

rigidly connected to said frame members by keys and by ring nuts 63 screwed onto the opposite ends of the sleeve. The exterior of said sleeve is machined so that it will turn freely in the pedestal 2 and the interior of said sleeve is machined so that it will serve as a bearing for the crank shaft 27, the outer end of said crank shaft being supported by a pedestal 2^a on the base plate. The pair of frame members 1 at the other side of the machine are rigidly connected at their rear ends to a horizontally-disposed shaft 64, shown in broken lines in Figure 5, that turns freely in the other pedestal 2 on the base plate, said shaft 64 being arranged in longitudinal alignment with the sleeve 62, so as to cause the movable supporting frame of the machine that carries the receiving table and the plate lifters to swing or oscillate about a horizontal axis 85 passing through the center of the shaft 64 and the crank shaft 27 that turns in the sleeve 62.

The mechanism that is used for tilting the supporting frame upwardly and rearwardly into the position shown in broken lines in Figure 2 when it becomes necessary to repair or remove the rolls of the mill preferably consists of a manually-operable means and a power driven means. The manually-operable frame tilting means herein illustrated consists of a vertically-disposed shaft 65 journaled in a bearing 66 on the base plate and provided with a hand wheel 67 and with a worm 68 that meshes with a worm gear 69 rigidly connected to the outer end of the shaft 64, previously referred to, which is rigidly connected to the frame members 1 at the right hand side of the machine. By turning the hand wheel 67 in one direction the worm 68 will co-operate with the worm gear 69 to tilt the supporting frame upwardly and rearwardly, and by turning said hand wheel in the opposite direction, said worm and worm gear will co-operate with each other to restore the supporting frame to its normal position at the rear of the rolls of the mill.

The power driven means that I prefer to use for bodily shifting the supporting frame into and out of operative relationship with the rolls of the mill consists of a pair of friction disks 70 rigidly connected to the transversely-disposed drive shaft 34 of the machine and arranged in spaced relation, as shown in Figure 4, a shaft 71, shown in broken lines in Figure 2, arranged at right angles to the drive shaft 34 and provided at its front end with a friction wheel 72 that is adapted to be moved into engagement with one or the other of the friction disks 70, and a beveled gear 73 on the rear end of the shaft 71 that meshes with a beveled gear 74 secured to the shaft 65 previously referred to that carries the worm which meshes with

the worm gear 68. The shaft 71 is journaled in a rockable bearing 75 on the base plate of the machine that is adapted to be swung to the right when it is desired to arrange the 5 friction wheel 72 in engagement with one of the friction disks 70 and swung to the left when it is desired to arrange said friction wheel 72 in engagement with the other friction disk. The bearing 75 is provided 10 with an operating handle 76 that projects upwardly from same, and springs 77 are combined with said handle 76, as shown in Figure 4, so as to normally maintain the bearing 75 in such a position that the friction wheel 72 does not contact with either 15 of the friction disks 70. If it is desired to tilt the supporting frame that carries the receiving table and plate lifters into the position shown in broken lines in Figure 2, the 20 handle 76 is moved in one direction so as to rock the bearing 75, and thus cause the friction wheel 72 to be engaged with one of the friction disks 70, thereby causing the shaft 71 to rotate and impart movement to the 25 worm shaft 65 in a direction to swing the supporting frame upwardly and rearwardly. When it is desired to restore said supporting frame to its normal position the handle 76 is moved in the opposite direction so as to cause 30 the friction wheel 72 to engage the other friction disk 70 on the drive shaft, thus causing the shaft 71 to revolve in the opposite direction, and impart rotary movement to the worm shaft 65 in a direction to cause 35 the supporting frame to move forwardly and downwardly into its normal position at the rear of the rolls of the mill. The friction disks and friction wheel just referred to and the other parts that are associated with same 40 are protected by a horizontally-disposed floor member 78 on which the workmen stand during the operation of removing or repairing the rolls of the mill, said floor member having a slot in same up through 45 which the operating handle 76 of the tilting mechanism projects.

Operation of machine.

Normally, the plate lifters C and C' and 50 the receiving table B are arranged in a horizontal position at the rear of the rolls of the mill so that a plate which is discharged rearwardly from said rolls will pass onto the receiving table. After the plate has passed 55 through the rolls of the mill the operator standing at the front of the mill depresses the foot treadle 43, thereby causing the crank shaft 27 to revolve and turn the rock shaft 26 in a direction to cause the actuating members 25 thereon to turn the pinion shafts 18 60 and 20 in a direction to move the plate lifters C and C' upwardly into the position shown in broken lines in Figure 3, said plate lifters coming to rest automatically when the crank shaft 27 has made a half revolution. The 65 operator then grasps the front end of the plate supported by the plate lifters and pulls said plate forwardly over the top roll of the mill, and he also depresses the foot treadle 43 so as to cause the crank shaft 27 to make 70 another half revolution, and thus rock the actuating members 25 in the opposite direction back to normal position, thereby causing the plate lifters to be moved downwardly into approximately horizontal alignment 75 with the receiving table.

If it is desired to tilt the front end of the receiving table B upwardly so as to discharge a plate from the rear end of said receiving table, the operator pulls forwardly 80 on the hand lever 59, thereby rocking the shaft 54 in a direction to cause the front end of the receiving table to move upwardly.

If it becomes necessary to repair or remove the rolls A and A' of the mill, the movable supporting frame of the machine that carries the receiving table and the plate lifters can be tilted upwardly and rearwardly into the position shown in broken lines in Figure 2, either by manually turning the worm shaft 85 90 65, or by manipulating the lever 76 in the proper direction, so as to transmit rotary movement to said worm shaft from the drive shaft 34 of the machine. After the work on the rolls of the mill has been completed the supporting frame and the parts carried thereby are restored to their normal position either by manually turning the worm shaft 95 100 65 in the proper direction, or by shifting the controlling lever 76 in the opposite direction so as to connect up the shaft 71 with the friction disk on the drive shaft 34 that is used to restore the supporting frame to its normal position.

In addition to the fact that the receiving 105 table, the plate lifters and the mechanism that is associated with said elements can be moved easily into and out of operative relationship with the rolls of the mill, my present plate lifting mechanism is compact and 110 inexpensive to manufacture, as it is equipped with relatively small counterweights that travel between the frame members of the machine and it is equipped with a simple form of operating mechanism for the plate lifters 115 that is constructed in such a way that the shock or back lash on the co-operating toothed elements that raise and lower the plate lifters will be absorbed automatically 120 when the plate lifters come to rest either in their elevated position or in their depressed position.

Having thus described my invention, what I claim as new and desire to secure 125 by Letters Patent is:

1. A plate lifting mechanism for rolling mills, comprising plate lifters arranged at the rear of the rolls of the mill, means for actuating said plate lifters, and means for enabling the plate lifters and the actuating 130

means for same to be moved bodily upwardly and away from the rolls of the mill so as to not interfere with workmen engaged in repairing or removing the rolls of the mill.

2. A plate lifting mechanism for rolling mills, comprising mechanism arranged at the rear of the rolls of the mill for receiving a plate discharged from the rolls and moving 10 said plate upwardly into such a position that it can be grasped by the operator standing at the front of the mill, and means for enabling said mechanism to be tilted upwardly and rearwardly into a position wherein it 15 does not obstruct the space at the rear of the rolls in which workmen stand during the operation of repairing or removing the rolls of the mill.

3. A plate lifting mechanism for rolling 20 mills, comprising plate lifters arranged at the rear of the rolls of the mill, an operating means for raising and lowering said plate lifters, and a movable supporting structure for carrying said plate lifters and said operating means and adapted to be tilted upwardly and rearwardly for the purpose described.

4. A plate lifting mechanism for rolling 30 mills, comprising a receiving table arranged at the rear of the rolls of the mill, means for lifting a plate from said table and moving it into such a position that it can be pulled forwardly over the top roll of the mill, and means for bodily shifting said 35 table and plate lifting means into and out of operative relationship with the rolls of the mill.

5. A plate lifting mechanism for rolling 40 mills, comprising a plate lifting means arranged at the rear of the rolls of the mill, and a tilttable supporting structure that carries said plate lifting means and which is adapted to be moved so as to shift said plate lifting means into and out of operative relationship with the rolls of the mill.

6. A plate lifting mechanism for rolling 50 mills, comprising a plate receiving table arranged at the rear of the rolls of the mill, means for lifting a plate from said table and moving said plate upwardly, a movable supporting structure that carries said table and plate lifting means, and means for bodily shifting said supporting structure into and out of operative relationship with the 55 rolls of the mill.

7. A plate lifting mechanism for rolling 60 mills, comprising a plate lifting means arranged at the rear of the rolls of the mill, an oscillating frame that carries said means, and means for actuating said frame so as to shift said plate lifting means into and out of operative relationship with said rolls.

8. A plate lifting mechanism for rolling 65 mills, comprising mechanism arranged at the rear of the rolls of the mill for receiv-

ing a plate discharged from the rolls and moving the plate upwardly into such a position that it can be grasped by the operator standing at the front of the mill, a movable frame that carries said mechanism, and 70 means for tilting said frame rearwardly so as to arrange said mechanism in a position where it does not interfere with workmen engaged in repairing or removing the rolls of the mill.

9. A plate lifting mechanism for rolling 75 mills, comprising a plate receiving table, a plate lifting means adapted to engage a plate on said table and move said plate upwardly, a movable supporting structure arranged at the rear of the rolls of the mill which carries said table and plate lifting means, and means for moving said supporting structure into one position wherein the parts carried by same are out of operative 80 relationship with the rolls of the mill and for thereafter returning said supporting structure to its normal position at the rear of the rolls.

10. A plate lifting mechanism for rolling 85 mills, comprising a plate lifting means, a swinging frame arranged at the rear of the rolls that carries said plate lifting means, means for swinging said frame about its axis of movement, and a manually-operable means and a mechanically-operable means for actuating said frame moving means.

11. A plate lifting mechanism for rolling 90 mills, comprising a plate lifting means, a 100 tilttable frame arranged at the rear of the rolls of the mill that carries said plate lifting means, and a manually-operable means for effecting the movement of said frame into and out of operative relationship with 105 the rolls of the mill.

12. A plate lifting mechanism for rolling 110 mills, comprising a plate lifting means, a tilttable frame arranged at the rear of the rolls of the mill that carries said plate lifting means, and a power-operated means for effecting the movement of said frame into and out of operative relationship with the rolls of the mill.

13. A plate lifting mechanism for rolling 115 mills, comprising a plate lifting means, a movable frame that carries said means, a stationary supporting structure on which said frame is pivotally mounted, and a worm and worm gear for oscillating said frame about its axis of movement so as to shift said plate lifting means into and out of operative relationship with the rolls of the mill.

14. A plate lifting mechanism for rolling 120 mills, comprising a plate lifting means, a movable frame arranged at the rear of the rolls of the mill that carries said plate lifting means, a stationary supporting structure on which said frame is pivotally mounted in such a manner that said frame can 125

be tilted upwardly and rearwardly away from the rolls of the mill, and means for tilting said frame.

15. A plate lifting mechanism for rolling mills, comprising a plate lifting means, a movable frame arranged at the rear of the rolls of the mill that carries said plate lifting means, a stationary supporting structure on which said frame is pivotally mounted in such a manner that said frame can be tilted upwardly and rearwardly away from the rolls of the mill, gearing for tilting said frame, a driving means, and means for enabling said gearing to be connected with 10 said driving means so as to tilt the frame into an inoperative position and for thereafter being connected with said driving means so as to restore the frame to its normal position.
20. 16. A plate lifting mechanism for rolling mills, comprising a plate lifting means, a movable frame arranged at the rear of the rolls of the mill that carries said plate lifting means, a stationary supporting structure on which said frame is pivotally mounted in such a manner that said frame can be tilted upwardly and rearwardly away from the rolls of the mill, gearing for tilting said frame, a drive shaft provided with a plurality of driving devices, and means for enabling said gearing to be connected with one of said driving devices when it is desired to tilt said frame into an inoperative position and for enabling said gearing to 25 be connected with the other driving device when it is desired to restore said frame to its normal position.

17. A plate lifting mechanism for rolling mills, comprising a plate lifting means, a movable frame arranged at the rear of the rolls of the mill that carries said plate lifting means, a stationary supporting structure on which said frame is pivotally mounted in such a manner that said frame can be tilted 40 upwardly and rearwardly away from the rolls of the mill, gearing for tilting said frame, a drive shaft provided with a pair of friction disks, a friction wheel operatively connected with said gearing, and means for enabling said friction wheel to be moved 45 into engagement with one of said disks to cause said frame to be tilted into an inoperative position and to thereafter be moved into engagement with the other disk, so as to 50 cause said frame to be restored to its normal position.

18. A plate lifting mechanism for rolling machines, comprising plate lifters arranged at the rear of the rolls of the mill, mechanism for bodily raising and lowering said plate lifters comprising oscillating actuating members, a rock shaft to which said actuating members are connected, and a crank shaft connected by a link to an arm on said 55 rock shaft.

19. A plate lifting mechanism for rolling mills, comprising plate lifters, means for raising and lowering said plate lifters comprising oscillating actuating members, a rock shaft to which said actuating members are connected, a crank shaft directly connected by means of a link with said rock shaft, a constantly rotating driving device, and a clutch under control of the operator in charge of the machine for enabling said 70 crank shaft to be connected with said driving device when it is desired to raise the plate lifters and when it is desired to thereafter depress said plate lifters.

20. A plate lifting mechanism for rolling mills, comprising plate lifters, means for raising and lowering said plate lifters comprising oscillating actuating members, a rock shaft to which said actuating members are connected, a crank shaft directly connected with said rock shaft, a constantly rotating driving member, a clutch for connecting said driving member with said crank shaft, and tripping devices under control of the operator in charge of the machine for causing 80 said clutch to become operative and to be thereafter rendered inoperative after the crank shaft has made a half revolution.

21. A plate lifting mechanism for rolling mills, comprising plate lifters, an operating means for said plate lifters comprising oscillating actuating members, segmental racks on said members and pinions meshing with said racks, means for operating said actuating members so as to raise and lower the plate lifters, and means for absorbing the shock or jar on said racks and pinions when said plate lifters come to rest either in their elevated or depressed position.

22. A plate lifting mechanism for rolling mills, comprising plate lifters, swinging links that carry said plate lifters, pinions joined rigidly to said links, oscillating segmental racks meshing with said pinions for moving said links so as to raise and lower said plate lifters, and means for absorbing the shock or jar on said pinions and racks due to sudden stopping of said plate lifters.

23. A plate lifting mechanism for rolling mills, comprising plate lifters, a counter-weighted mechanism for raising and lowering said plate lifters comprising oscillating segmental racks and pinions that mesh with same, and means for absorbing the shock or jar on said racks and pinions due to sudden stopping of the plate lifters.

24. A plate lifting mechanism for rolling mills, comprising plate lifters, counter-weighted links that carry said plate lifters, shafts rigidly connected with said links and provided with pinions, oscillating segmental racks meshing with said pinions, and arms on said shafts connected with springs in such a manner that they will absorb the shock or jar on said racks and pinions.

caused by sudden stopping of the plate lifters.

25. A plate lifting mechanism for rolling mills, comprising a receiving table arranged at the rear of the rolls of the mill, vertically-movable plate lifters arranged at opposite sides of said table, a supporting frame comprising a pair of parallel frame members arranged at each side of said table, swinging links carried by said supporting frame and pivotally connected to said plate lifters, counterweights on said links that travel between the pairs of frame members, and actuating members for said links arranged between the pairs of frame members at the opposite sides of the machine.

26. A plate lifting mechanism for rolling mills, comprising a receiving table arranged at the rear of the rolls of the mill, a frame comprising pairs of frame members arranged at opposite sides of said table, a pair of counterweighted swinging links arranged between each pair of frame members, plate lifters arranged at opposite sides of said receiving table and pivotally connected to said links, and an oscillating actuating member for each pair of links arranged between the pair of frame members between which the links travel.

27. A plate lifting mechanism for rolling mills, comprising a plate receiving table arranged at the rear of the rolls of the mill, vertically-movable plate lifters arranged at opposite sides of said table, a horizontally-disposed shaft, a sleeve on said table journaled on said shaft, an arm rigidly connected to said sleeve, and a system of links and levers extending forwardly to an operating

device at the front of the mill for tilting said table so as to discharge a plate therefrom.

28. A plate lifting mechanism for rolling mills, comprising a receiving table arranged at the rear of the rolls of the mill, vertically-movable plate lifters arranged at opposite sides of said table for moving a plate upwardly into position to be grasped by the operator standing at the front of the mill, a counterweighted operating mechanism for raising and lowering said plate lifters, a rockable frame that carries said table, plate lifters and operating mechanism for the plate lifters, means for tilting said table to discharge a plate therefrom, and means for enabling said frame to be moved bodily into a position where it does not interfere with workmen engaged in repairing or removing the rolls of the mill.

29. A plate lifting mechanism for rolling mills, comprising plate lifters arranged at the rear of the rolls of the mill, a pair of swinging links combined with each of said plate lifters for raising and lowering the same, and adjustable connections between the plate lifters and the links which support one end of the plate lifters.

30. A plate lifting mechanism for rolling mills, comprising plate lifters arranged at the rear of the rolls of the mill, means for moving said plate lifters upwardly into such a position that the front ends of same are inclined downwardly towards the top roll of the mill, and means for enabling the angle of said plate lifters to be changed so as to vary the downward tilt of said plate lifters.

THOMAS McCABE.
